The ornamental design for a portion of an audiovisual communication device, as shown and described.

DESCRIPTION

FIG. 1 is a front perspective view of a portion of an audiovisual communication device showing my new design; FIG. 2 is a front view thereof;

FIG. 3 is a rear view thereof;

FIG. 4 is a right side view thereof;

FIG. 5 is a left side view thereof; and,

FIG. 6 is a top view thereof.

The unshown bottom forms no part of the claimed design. The broken lines are for illustrative purposes only and form no part of the claimed design.
